UNITED STATES PATENT OFFICE

103,096

DESIGN FOR AN AUTOMOBILE

Douglas Frederick Harold Fitzmaurice, London,
England

Application November 14, 1936, Serial No. 65,913
In Great Britain July 4, 1936

Term of patent 14 years

To all whom it may concern:

Be it known that I, Douglas Frederick Harold Fitzmaurice, a subject of the Kingdom of Great Britain, residing at London, England, have invented a new, original, and ornamental Design for an Automobile, of which the following is a specification, reference being had to the accompanying drawing, forming a part thereof.

In the drawing:—

Fig. 1 is a perspective view showing the front and right side of the automobile.

Fig. 2 is a perspective view showing the rear and left side of the automobile.

I claim:—

The ornamental design for an automobile as shown.

DOUGLAS FREDERICK

HAROLD FITZMAURICE,
